UNITED STATES PATENT OFFICE.

LEWIS H. JOHNSON, OF BLOOMFIELD, NEW JERSEY. ASSIGNOR, BY MESNE ASSIGNMENTS, TO WESTERN ELECTRIC COMPANY, INCORPORATED, A CORPORATION OF NEW YORK.

TELEPHONE SYSTEM.

1,353,910.

Specification of Letters Patent. Patented Sept. 28, 1920.

Application filed July 25, 1914. Serial No. 858,139.

To all whom it may concern:

Be it known that I, LEWIS H. JOHNSON, a citizen of the United States, residing at Bloomfield, in the county of Essex and State 5 of New Jersey, have invented certain new and useful Improvements in Telephone Systems, of which the following is a full, clear, concise, and exact description.

This invention relates to telephone systems of the central energy multiple type.

The object of this invention is to provide a telephone system in which a calling subscriber, once being answered by the central office operator, may regain control of his 15 line signal at any time before the called subscriber answers. A further object of this invention is to provide a telephone system in which two connected subscribers, after completing a conversation, may regain control 20 of their line signals by restoring their receivers to the switchhooks. A further object of this invention is to provide a telephone system in which there is absolute secret service.

25 In accordance with the various features of this invention, generally speaking, there are provided subscribers' lines terminating at the central office, link conductors thereat for interconnecting the subscribers' lines, line 30 signals for the subscribers' lines, cut-off relays for the line signals, and means associated with the link conductors and controlled by the subscribers in the operation of their switchhooks for releasing the cut-off relays, so that subsequent operation of the switchhooks will cause the operation of 35 the line signals. There is also provided means for altering the electrical condition of the switching terminals of a line and 40 means responsive to the original electrical condition of the switching terminals for associating an operator's telephone set with a line, but irresponsible to the altered electrical condition of the switching terminals, 45 thereby preventing the association of the operator's telephone set with a line already in use.

This invention is illustrated in the accompanying drawing, in which an apparatus is 50 shown in its normal and unactuated condition.

There is shown in the drawing a telephone system containing one embodiment of this

invention and comprising subscribers' stations, A and B, terminating in a plurality 55 of jacks at the central office and a cord circuit C located thereat for interconnecting the subscribers' stations. It is believed that this invention will be fully understood from a description of the operation of the system 60 shown in the drawing and it will be so described.

Supposing subscriber A wishes to converse with subscriber B, A removes his receiver from the switchhook, thereby completing a circuit from the live pole of battery 5, through a winding of line relay 6, normally closed contact 7 of cut-off relay 8, line wires 9 and 10, normally closed contact 11 of cut-off relay 8 and the other winding of line relay 6 to the other side of battery 5. Current in this path actuates the line relay 6, completing a circuit for the line signal 12. The operator, observing the line signal 12, inserts her answering plug 75 in the jack indicated, thereby completing a circuit from the live pole of battery 13, through windings 14 and 15 of double-wound relay 16, sleeve contact 18 of the answering plug, sleeve contact 19 of the answering jack and the winding of cut-off relay 8, to ground. Current in this path actuates double-wound relay 16 which attracts its armatures, closing contacts 25 and 26. Closure of contact 25 completes a circuit from the live pole of battery 27, normally closed contact 28 of relay 29, normally closed contact 30 of relay 31, contact 25 and winding 15 of double-wound relay 16, sleeve contact 18 of the plug, sleeve contact 19 of the jack and the winding of cut-off relay, to ground. This circuit just traced (to the winding 15) forms a short-circuit of the winding 14 of the double-wound relay 16, permitting the actuation of cut-off 85 relay 8, which severs the circuit of the line relay 6, which in releasing, effaces the line signal 12. The closing of contact 26, when the double-wound relay 16 is actuated, establishes a circuit from the live pole of battery 13, through contact 26 of the double-wound relay 16, normally closed contact 32 of relay 33, the winding of relay 34 and normally closed contact 35 of relay 31, to ground. Current in this path actuates relay 34, connecting the operator's telephone 90 95 100 105

set across the talking strands 36 and 37 of the cord circuit. When the answering plug was inserted in the answering jack of the calling line A, a circuit was established from the live pole of battery 40 through normally closed contact 41 of relay 42, a winding of relay 43, talking strand 36 and tip contact 44 of the plug, tip contact 45 of the answering jack, line wires 10 and 9, ring contact 46 of the answering jack, ring contact 47 of the plug, talking strand 37 of the cord circuit, the other winding of relay 43 and normally closed contact 48 of relay 42, to ground. Current in this path actuates relay 43, opening the normally closed contact 49 and closing the normally open contact 50, thereby preventing the operation of supervisory signal 51. When contact 50 of the relay 43 is closed, a circuit 20 is established from the live pole of battery 13, through contact 26 of the double-wound relay 16, contact 50 of relay 43 and the winding of relay 29, to ground. Current in this path actuates relay 29, which opens contact 28 and closes contacts 52 and 53. Closure of contact 53 establishes a circuit for relay 31 from the live pole of battery 13, through contact 26 of relay 16, the winding of relay 31, contact 53 of relay 29 and contact 35 of relay 31, to ground. Current in this path actuates relay 31, which opens contact 35 and closes contact 54, thereby establishing a locking circuit for itself. The closure of contact 52, when relay 29 is actuated, prevents the removal of the short-circuit of winding 14 of the double-wound relay 16.

The operator now asks the desired number of the calling subscriber. Finding the desired number to be that of the subscriber B, the operator touches the tip of the calling plug to the sleeve of the jack corresponding to B's line to determine the idle or busy condition thereof. If the line tests idle, the calling plug is inserted in the jack, completing a circuit from the live pole of battery 60, through windings 61 and 62 of double-wound relay 63, the winding of relay 33, sleeve contact 64 of the calling plug, sleeve contact 59 of the jack and the winding of cut-off relay 58, to ground. Current in this path actuates double-wound relay 63, which establishes a circuit from the live pole of battery 65, contact 66 of relay 63, contact 67 of relay 68 and supervisory signal 69, to ground, actuating the supervisory signal. The actuation of relay 63 also completes a circuit from the live pole of battery 70, through contact 71 of relay 72, contact 73 and winding 62 of relay 63, the winding of relay 33, sleeve contact 64 of the cord plug, the sleeve contact 59 of the jack and the cut-off relay 58, to ground. This circuit (to the winding 62) short-circuits winding 61 of relay 63, and in so doing, permits the operation of the relay 33 and the cut-off relay 58. The actuation of relay 33 opens the circuit of the relay 34 at contact 32, disconnecting the operator's telephone set from the talking strands 36 and 37 of the cord circuit. 70 The actuation of the cut-off relay 58 prevents the operation of line signal associated with B's line when the receiver is removed from the switchhook. When relay 33 was actuated, contact 74 thereof was closed. The operator now depresses any one of the plungers 75 of the ringing key 76 to send ringing current out on B's line and in so doing, closes the way-down contact 77 of the ringing key 76 which completes a circuit from 80 the live pole of battery 13, through contact 26 of relay 16, contact 74 of relay 33, winding of relay 78 and way-down contact 77, to ground. Current in this path actuates relay 78 which, in attracting its armatures, completes a locking circuit for itself through contact 79 thereof, and contact 80 of marginal relay 85. Relay 78 in operating, also closes contacts 86 and 87 thereof, completing a circuit from the source of ringing current 90 connected to the ringing key 76, through the winding of marginal relay 85, contact 86 of relay 78, ring contact 88 of the plug, ring contact 84 of the jack, line wire 83, bell 82, condenser 81, line wire 98, tip contact 99 of the jack, tip contact 89 of plug and contact 87 of relay 78, to ground. Ringing current in this path operates the bell 82 at station B, but since relay 85 is marginal, it will not operate when in series with the bell 82 and the condenser 81 at station B, but will operate when the bell and condenser are shunted by a low-resistance path. Subscriber B, upon removing his receiver from the switchhook, closes a path of 105 low resistance for the ringing current, thereby permitting a greater flow of current through the relay 85. Relay 85 is thereupon actuated, opening the locking circuit of relay 78 at contact 80 of relay 85. Relay 78 thereupon releases, opening contacts 86 and 87 thereof, thereby removing the ringing current from the called line, and closing contacts 90 and 91 in the talking strands of the cord circuit. Closure of contacts 90 and 91 completes a circuit from the live pole of battery 70, through contact 93 of relay 72, a winding of relay 68, contact 94 of relay 34, contact 90 of relay 78, ring contact 88 of the plug, the ring contact 84 of the jack, line 110 wires 83 and 98, the tip contact 99 of the jack, tip contact 89 of the plug, contact 91 of relay 78, contact 95 of relay 34, the other winding of relay 68, and contact 96 of relay 72, to ground. Current in this path actuates relay 68, which opens the circuit of the supervisory signal and closes contact 97. 115 In a number of instances it happens that the calling subscriber, after communicating to the central office operator the number 120 125 130

of the line desired, fails to get connection with the line desired. In some of these cases the operator may have failed to ring the line wanted, or having rung the line, the called party does not answer. In any event, it is desirable that the calling subscriber be able to attract the attention of the operator and obtain connection with the operator's telephone set, whereupon the subscriber may call for another line, if he so desires. In the ordinary telephone systems now in use, in order to so attract the attention of the operator, the subscriber must operate his switchhook repeatedly to flash the supervisory signal. During the busy periods when an operator is handling a large number of calls, her attention is directed principally to the line signals, so that there are times when the supervisory signals may be flashing for a considerable length of time before the operator notices them. Now in accordance with this invention, when the calling subscriber desires, at any time before the called subscriber answers, to attract the attention of the operator, he merely operates his switchhook once and releases it. This results in the operation of the line signal, which immediately attracts the attention of the operator. Suppose that subscriber A, after communicating to the central office operator the number desired and the operator has or has not inserted the calling plug within the jack of the called line, subscriber A may regain control of his line lamp, assuming that the called subscriber has not answered. The restoration of the receiver to the switchhook by subscriber A opens the circuit of relay 43 which, in releasing, opens contact 50 thereof and closes contact 49, completing a circuit for supervisory or disconnect signal 51. The opening of contact 50 opens the circuit of relay 29 which, in releasing, opens contact 52 and closes contact 28. The opening of contact 52 opens the short-circuit of winding 14 of the double-wound relay 16. Winding 14 is therewith included with winding 15 in the circuit through the cut-off relay 8. The cut-off relay 8 is marginal and will not be actuated, or will not remain actuated, when both windings 14 and 15 of relay 16 are included in circuit therewith, but will be actuated when included in series with winding 15 only. Therefore, the removing of the short-circuit of the winding 14 of relay 16 permits the cut-off relay 8 to release, closing its contacts 7 and 11. The closing of contact 28, before referred to, completes a circuit from the live pole of battery 27, through contact 28 of relay 29, contact 92 of relay 31, winding of relays 42 and 72, to ground. Current in this path actuates relays 42 and 72 which, in attracting their armatures, remove battery from the talking strands of the cord circuit. It will now be seen that the

removal of the receiver from the switchhook by A causes the operation of line relay 6 and the operation of the line signal 12.

On the other hand, if subscriber B has answered, subscriber A cannot regain control of line signal 12 until subscriber B restores his receiver to the switchhook. When subscriber B answers, contact 97 of relay 68 will be closed, thereby establishing a second circuit for relay 29. The first circuit for relay 29 is controlled by subscriber A and may be traced from the live pole of battery 13, through contact 26 of relay 16, contact 50 of relay 43, and the winding of relay 29, to ground. The second circuit for relay 29 is controlled by subscriber B and may be traced from the live pole of battery 65, through contact 66 of relay 63, contact 97 of relay 68, and the winding of relay 29, to ground. The restoration of the receiver to the switchhook by B opens the circuit of relay 68 which, in releasing, opens contact 97 and closes contact 67, completing a circuit for the supervisory or disconnect signal 69. The opening of contact 97 opens the second circuit of relay 29, but the relay 29 will remain actuated, for the first circuit thereof is still closed. However, when subscriber A restores his receiver to the switchhook, the first circuit will be opened and relay 29 will release. Subscriber A then regains control of line signal 12 in the manner hereinbefore described. In a similar manner subscriber B regains control of his line signal; that is when relay 72 is actuated upon the release of relay 29, contact 71 is opened, removing the short circuit of winding 61 of the doubly wound relay 63. Both relays 33 and 58 are marginal, and will not operate, or will not remain operated, when both windings 61 and 62 of relay 68 are in circuit therewith, but will be operated when only winding 62 is in circuit therewith. Therefore, removal of the short circuit of the winding 61 of relay 63, permits the release of relays 33 and 58. The cut-off relay 58, in releasing, closes the contacts controlled thereby. The release of relay 33 closes contact 32 in the circuit of relay 34, but since relay 31 is actuated and relay 29 is released, relay 34 is prevented from being actuated, hence the operator's telephone set cannot be connected to the talking strands of the cord circuit.

When the operator withdraws the plugs of the cord circuit from the jacks, all apparatus is returned to its normal position.

The telephone system shown in the drawing embodies as a feature of this invention means for preventing the operator from listening in on any line except when answering a calling subscriber. In the first place, the system is so arranged that the operator's telephone set is automatically associated with the talking strands of the cord circuit, and can be associated therewith in no other way.

Suppose that connection is established between subscribers' stations A and B through the cord circuit C, and an operator attempts to connect another cord circuit (like that shown in the drawings) with either line A or line B, the operator's telephone set in the second mentioned cord circuit will not be associated with the talking strands of this cord circuit. When the first cord circuit is connected with a jack corresponding to each of the lines A and B, the sleeves of the jacks will be raised to a definite potential by the current from batteries 27 and 70, and winding 14 of relay 16 and winding 61 of relay 63 will be short-circuited. Now suppose that the answering plug of a second cord be inserted in any one of the multiple jacks of line A, the relay 16 of the second cord will be prevented from operating, due to the fact that relay 16 of the first or connected cord circuit is already operated and the winding 14 thereof is short-circuited, forming a short circuit of the relay 16 in the second cord circuit. Likewise should the answering plug of the second cord circuit be inserted in any of the multiple jacks of line B, relay 16 of the second cord circuit will be prevented from operating, due to the fact that relay 63 of the first or connected cord circuit is already operated and the winding 61 thereof is short-circuited, forming a short circuit of the relay 16 in the second cord circuit. Since relay 16 controls the operation of relay 34, the association of the operator's telephone set with the talking strands of the second cord circuit is prevented. It will also be noted that in the system hereinbefore described, it is impossible to ring on a busy line, for since relay 63 does not operate, the operation of relay 33 is prevented.

While in this description a plurality of batteries has been referred to, it is to be understood that a common battery may be substituted for all of these, and such is the usual practice.

What is claimed is—

1. A telephone system comprising subscribers' lines terminating at a central office, link conductors thereat for interconnecting said lines, line signals for said lines, a double-wound relay associated with each end of said link conductors, one of said windings being normally short-circuited when said link conductors are connected with said lines, a cutoff relay for the line signal energized over a circuit including the non-short-circuited winding of said double-wound relay, and means controlled by the operation of a subscriber's switch-hook for removing the short circuit from said short-circuited winding to release said cut-off relay, whereby the subscribers may regain control of said line signals.
2. A telephone system comprising sub-

scribers' lines terminating at a central office, line signals thereat for said lines, link conductors at said office for interconnecting said lines, a relay associated with the answering end of said link conductors, said relay having a plurality of windings, one of which is normally short-circuited when said link conductors are associated with a calling line, a cut-off relay for the line signal of the calling line energized over a circuit including a non-short-circuited winding of said first mentioned relay, and electromagnetic means controlled by the calling subscriber in the operation of his switchhook for removing the short circuit of the short-circuited winding of said first mentioned relay for releasing said cut-off relay, whereby said calling subscriber may regain control of his line signal at any time before a called subscriber answers.

3. A telephone system comprising a telephone line terminating at a central office, a line signal for the line, a link circuit, a cut-off relay associated with the line for controlling the line signal and actuated upon connection of the link circuit with the line, a supervisory relay in the link circuit deenergized upon the opening of the telephone line, a resistance coil, and a relay responsive to the deenergization of the supervisory relay for including the resistance coil in circuit with the cut-off relay to cause the release thereof.

4. A telephone system comprising a telephone line terminating at a central office, a line signal for the line, a link circuit connected with the line, a double-wound relay in the link circuit having one winding normally short-circuited when the link circuit is connected with the line, a cutoff relay for the line signal energized over a circuit including the non-short-circuited winding of the double-wound relay and means controlled over the line for removing the short circuit from the normally short-circuited winding to release the cutoff relay thereby to restore the line signal to the control of the line.

5. A telephone system comprising a telephone line terminating at a central office, a line signal for the line, a link circuit connected with the line, a cutoff relay associated with the line, a double-wound relay in the link circuit having one winding normally short-circuited when the link circuit is connected with the line, a cutoff relay for the line signal energized over a circuit including the non-short-circuited winding of the double-wound relay, a relay in the link circuit controlled over the telephone line and means rendered effective by the response of the line-controlled relay upon the opening of the line to remove the short circuit from the short-circuited winding to release the

cutoff relay thereby to restore the line signal to the control of the line.

6. A telephone system comprising telephone lines, terminating at a central office, link circuits for interconnecting the lines, line signals for the lines, a double-wound relay in each end of the link circuit, each relay having one winding normally short circuited when the link circuit is connected with the lines, a cutoff relay for each line signal energized over a circuit including the non-short-circuited winding of the associated double-wound relay, a relay in each end of the link circuit controlled over the respective telephone lines and means rendered effective by the response of the line-controlled relays upon the opening of the telephone lines for removing the short circuits from the short-circuited windings to release the cutoff relays thereby to restore the line signals to the control of the lines.

7. A telephone system comprising a telephone line terminating at a central office, a line signal for the line, a link circuit connected with the line, a pair of relay windings in the link circuit, one of which is normally short circuited when the link circuit is connected with the line, a cutoff relay for the line signal energized over a circuit including a non-short-circuited winding of the pair of relay windings, a supervisory relay in the link circuit deenergized upon the opening of the telephone line, a relay responsive to the deenergization of the supervisory relay for opening the short circuit of the relay winding thereby to include this winding in circuit with the cutoff relay whereby the cutoff relay is released to restore the line signal to the control of the telephone line, a supervisory signal and an operating circuit therefor including a contact of the supervisory relay and a contact controlled by one of the pair of relay windings.

8. A telephone system comprising a telephone line terminating at a central office, a line signal for the line, a link circuit, a cutoff relay for the line energized upon connection of the link circuit therewith for controlling the line signal, a supervisory relay in the link circuit responsive to the opening of the telephone line, a relay winding included in circuit with the cutoff relay by the response of the supervisory relay to cause the release of the cutoff relay, a supervisory signal and an operating circuit therefor including a contact of the supervisory relay and a contact controlled by the relay having said winding.

9. In a telephone system comprising subscribers' lines having switching terminals, link circuits having coöperating switching terminals, line signals for the lines, cutoff relays for the line signals, a local circuit for

each end of the link circuit including a co-operating pair of switching terminals, one of the cutoff relays and a source of current and means controlled by either of the subscribers for decreasing the flow of current in the local circuits to a predetermined positive value thereby to release the cutoff relays.

10. A telephone system comprising subscribers' lines having switching terminals, link circuits having coöperating switching terminals, line signals for the lines, cutoff relays for the line signals, a local circuit for each end of the link circuit including a co-operating pair of switching terminals, one of the cutoff relays and a source of current, a relay in each end of the link circuit controlled over the respective connected lines and circuit connections rendered effective by the line-controlled relays in response to the opening of the connected telephone lines for decreasing the flow of current in the local circuits to a predetermined positive value thereby to release the cutoff relays.

11. A telephone system comprising telephone lines terminating at a central office, a link circuit including talking conductors for interconnecting the lines, a source of current normally connected with the talking conductors for supplying talking current to one of the lines, a relay in the link circuit connected between the source of current and the talking conductors and controlled over a connected line and circuit connections rendered effective by the line-controlled relay in response to the opening of one of the telephone lines for disconnecting the source of current from the talking conductors thereby removing the line-controlled relay from control of the line.

12. A telephone system comprising telephone lines terminating at a central office, a link circuit including talking conductors for interconnecting the lines, a source of current normally connected with the talking conductors for supplying talking current to one of the lines, a relay in the link circuit connected between the source of current and the talking conductors and controlled over a connected line, a relay energized upon the deenergization of the line-controlled relay in response to the opening of the telephone line for disconnecting the source of current from the talking conductors thereby removing the line-controlled relay from control of the line and a locking circuit for the last-mentioned relay completed thereby.

13. A telephone system comprising calling and called lines, a line signal for the calling line, a link circuit for connecting the lines, a cutoff relay for the calling line for controlling the line signal thereof and actuated upon connection of the link circuit therewith, a resistance coil, a source of ring-

- 6
17. A telephone system comprising calling and called telephone lines, a link circuit connected with the calling line, a source of ringing current, a ringing relay in the link circuit adapted when energized to connect 70 a source of ringing current with the called line, a control relay energized upon connection of the link circuit with the called line for controlling the energization of the ringing relay, a relay in the link circuit controlled over the connected calling line, a local relay responsive to the deenergization of the line-controlled relay upon the opening of the calling telephone line and a resistance coil included in circuit with the control relay upon the response of the local relay for releasing the control relay whereby ringing current is disconnected from the called line. 75
18. A telephone system comprising calling and called telephone lines terminating at a central office, a link circuit for connecting the lines, an operator's telephone set, a listening relay in the link circuit responsive to the connection of the link circuit with the calling line to connect the operator's telephone set therewith, a source of ringing current, a ringing relay for connecting the source of ringing current to the called line, an energizing circuit for the 95 ringing relay, a relay controlling a contact in the energizing circuit of the ringing relay and also controlling the deenergization of the listening relay energized in response to the connection of the link circuit with the 100 called line and means in the link circuit controlled over the calling telephone line and rendered effective by the opening of said calling telephone line to cause the disconnection of ringing current from the called line. 105
19. In a telephone exchange system, subscribers' lines terminating at a central office, a plurality of terminals, a plurality of link circuits for interconnecting the lines, an operator's telephone set adapted for connection with each link circuit, a relay associated with each link circuit operating upon connection thereof with a calling telephone line to control the inclusion of the operator's telephone set in circuit, means controlled by 115 each relay and rendered effective by the operation thereof to prevent the operation of the relay of another link circuit when connected with the same line, a source of ringing current, a ringing relay for connecting 120 the source of ringing current with a called line, an energizing circuit therefor, a local circuit relay energized upon the connection of the first link circuit with a called line to cause the release of the operator's telephone 125 set controlling relay and to close a contact in the energizing circuit of the ringing relay, a relay in the first link circuit controlled over the connected calling line and circuit connections rendered effective by the line- 130
- ing current, means for connecting the source of ringing current with the called line and means controlled over the calling telephone line for including a resistance coil in circuit 5 with the cutoff relay to cause the release thereof and for causing the disconnection of the source of ringing current from the called line.
14. A telephone system comprising a calling telephone line, a line signal therefor, a cutoff relay for the calling line energized upon connection of the link circuit therewith for controlling the line signal, a second telephone line, a source of ringing current, means for connecting the source of ringing current with the second line, a supervisory relay in the link circuit responsive to the opening of the calling line, a relay winding included in circuit with the cutoff relay by 15 the response of the supervisory relay to release the cutoff relay, means rendered effective by the response of the supervisory relay for causing the disconnection of the source of ringing current from the second line and a supervisory signal controlled by 20 the supervisory relay and the relay having said winding.
15. In a telephone system comprising a calling telephone line, a link circuit including talking conductors connected with the calling line, a source of current normally connected with the talking conductors for supplying talking current to the calling line, a relay in the link circuit connected between the source of current and the talking conductors and controlled over the calling line, a second line, means for connecting a source of ringing current therewith and circuit connections rendered effective by the 25 line-controlled relay in response to the opening of the calling line for disconnecting the source of current from the talking conductors thereby removing the line-controlled relay from control of the calling line and for causing the disconnection of the ringing current from the second line. 30
16. A telephone system comprising calling and called telephone lines, a link circuit connected with the calling line, a source of ringing current, a ringing relay in the link circuit adapted when energized to connect the source of ringing current with the called line, a control relay energized upon connection of the link circuit with the called line for controlling the energization of the ringing relay, a relay in the link circuit controlled over the connected calling line and a relay responsive to the deenergization of the line-controlled relay upon the opening of 35 the calling line for decreasing the flow of current in the energizing circuit of the control relay to a predetermined positive value whereby the control relay is released to cause the disconnection of ringing current 40 from the called line.

controlled relay in response to the opening of the calling telephone line to cause the release of the local-circuit relay whereby ringing current is disconnected from the 5 called line.

20. In combination with a calling telephone line, a plurality of connecting terminals for the line located at operators' positions of a central office switchboard, a line 10 signal for the line, a cutoff relay controlling the line signal, operators' link circuits having associated operators' telephones and including means effective when one of the link circuits and associated operator's telephone 15 is connected to one of the terminals whereby a second link circuit and operator's telephone is barred from operative connection with another of the terminals, a relay in the

engaged link circuit controlled over the telephone line, a called telephone line, a source 20 of ringing current, means for connecting the source of ringing current with the called line when the engaged link circuit is connected therewith and circuit connections rendered effective by the line-controlled relay 25 in response to the opening of the calling telephone line for causing the release of the cutoff relay and the disconnection of ringing current from the called line.

In witness whereof, I hereunto subscribe 30 my name this 23rd day of July, A. D. 1914.

LEWIS H. JOHNSON.
